CLAIM

The ornamental design for a biomorphic container, as shown and described.

DESCRIPTION

FIG. 1 is a top isometric view of a biomorphic container;

FIG. 2 is a bottom isometric view of the biomorphic container of FIG. 1;

FIG. 3 is a top planar view of the biomorphic container of FIG. 1;

FIG. 4 is a bottom planar view of the biomorphic container of FIG. 1;

FIG. 5 is a front elevation view of the biomorphic container of FIG. 1;

FIG. 6 is a rear elevation view of the biomorphic container of FIG. 1;

FIG. 7 is a side elevation view of the biomorphic container of FIG. 1, showing a first side of the biomorphic container; and,

FIG. 8 is a side elevation view of the biomorphic container of FIG. 1, showing a second side of the biomorphic container.
